UNITED STATES PATENT OFFICE

ABRAHAM PODEL, OF NEW YORK, N. Y., ASSIGNOR TO ANCHOR CAP & CLOSURE CORPORATION, OF LONG ISLAND CITY, NEW YORK, A CORPORATION OF NEW YORK

HERMETIC SEAL

Application filed July 21, 1927. Serial No. 207,453.

The present invention relates to sealed packages and more particularly to packages sealed by screw caps.

Screw caps are desirable for many sealed products primarily because they may be sealed and resealed without the use of expensive machinery. Usually a sealing ring or disc is placed in the upper part of the cap or skirt to form an edge seal with the rim 5 of the container; or the flat ring gasket is placed on a suitable shoulder of the container to engage the lower edge of the flange 10 of the cap. In either case the seal is formed by direct vertical pressure which, due to the elasticity of the gasket, is constantly pressing the cap upwardly. Slight imperfections 15 on the shoulder or rim of the container are fatal to the seal when the seal is formed on the edge of the container and both the gasket and rim become sticky and contaminated. The gaskets must be placed on the container by hand prior to the sealing operation. Special forms of gaskets are required in some instances to fit the caps and the gaskets are 20 glued to the caps in other instances.

The present invention eliminates the difficulties enumerated above by providing a screw cap adapted to seat a gasket in the skirt thereof, and to form a side seal on a 25 suitable container. The cap and gasket may be assembled by automatic machinery and shipped assembled to packers who may likewise apply them to packages by automatic machinery. The required sealing forces are 30 reduced to a minimum since the sealing is accomplished by a combined downward and outward pressure which gives a wedging action effected by the annular inclined sealing zone. Adherence by the caps to the 35 container is minimized due to the fact that the gaskets tend to expand the skirt of the cap and to separate the metal and glass.

An object of the invention is to provide an effective and inexpensive side seal by 40 wedging the gasket between the skirt of the cap and the inclined side wall of the container below the rim thereof.

Another object of the invention is to provide a sealed package, the parts of which 45 may be assembled by automatic machinery

thereby eliminating the necessity of skilled labor.

A further object of the invention is to minimize the difficulty encountered in removing screw caps by providing a seal 55 which tends to expand the cap and to separate the glass and metal.

Other and further objects of the invention will be obvious to one skilled in the art upon an understanding of the illustrated 60 embodiment, and various advantages will occur to one skilled in the art upon application of the invention in practice.

A preferred embodiment has been chosen for purposes of illustration and description 65 and is shown in the accompanying drawings, wherein

Fig. 1 is a side elevational view of a package sealed in accordance with the present invention.

Fig. 2 is a sectional view of one form of closure cap;

Fig. 3 is a fragmentary sectional view showing the cap applied to a container; and

Fig. 4 is a fragmentary sectional view 75 illustrating another form of cap applied to a container.

Referring more particularly to the drawings there is shown a container 1 having an inclined sealing zone 2 adjacent the mouth thereof as shown in Fig. 3. Suitable screw threads 4 are provided below the sealing zone to facilitate the application of a closure and a suitable shoulder 5 is provided below the screw threads to improve the appearance of 80 the container.

The closure cap 6 preferably comprises a cover portion 7 and a depending skirt 8. A suitable bead 9 is formed in the skirt by provision of an outwardly extending shelf 10 having downwardly and inwardly extending portions 11 adapted to receive and support the gasket 12. Below the bead are suitable screw threads 14 which extend to 85 the bottom of the cap where a wire edge 15 protects and reinforces the lower portion of the cap.

In Fig. 4 another form of closure and container is shown. The bead 9 is formed at the lower edge of the skirt of the cap and has 90

the lower edge of the skirt turned inwardly to support a gasket. The inclined sealing zone 17 is below the screw threads and merges with the shoulder 5 on the container.

In either of the caps shown the gaskets and closures may be assembled by automatic machines, one form of which feeds gaskets to an assembling mandrel which draws the gaskets about a cylindrical form by forming two diametric loops therein and inserts them within the closure permitting them to return to their normal shape in the bead of the cap. When once assembled the closures and gaskets may be shipped and handled without disturbing the relation of the gaskets. They may be fed by automatic machines and applied to the containers without the use of skilled labor. When the cap is applied the gasket 12 whether at or above the lower edge of the skirt, engages the inclined sealing zone 2 or 17 on the receptacle and as the closure is screwed further on the container the gasket is wedged against the sealing zone. By suitable regulation of the amount of incline, the pressure exerted in a lateral direction may be increased considerably beyond the pressure applied in a vertical direction. In this way a minimum rotative effort applied to the cap will form an effective seal. The danger of the closure freezing to the glass container is minimized due to the fact that there is a constant tendency of the gasket to press the skirt of the cap away from the metal of the container thereby facilitating ready removal thereof.

Since the gasket is below the rim of the container, there is little likelihood of its being contaminated by the contents thereof. Upon removal of the cap the gasket remains in the bead thereof permitting sealing and resealing of the container.

It will be noted that the above invention provides a screw cap and container adapted to form an effective hermetic side seal. The closure may be applied with a minimum rotative effort due to the fact that it is wedged between the closure and the container. Adherence of the closure to the container is minimized and the removal of the cap facilitated. Necessity for skilled labor is eliminated and the amount of labor required in sealing the packages is minimized by providing a construction where the various operations may be performed by machinery. Further, the resulting package is such that it is fully capable of withstanding the rough handling to which it may be subjected in transportation.

As various changes may be made in the above embodiment without departing from the spirit of the invention it is to be understood that all matter herein is to be taken as illustrative and not in a limiting sense.

Having thus described my invention, I claim:

1. A sealed package comprising a container having screw threads thereon for engagement with a closure and an inclined surface for engagement with a gasket, a closure cap having a cover portion and a depending skirt, a gasket in the skirt of said cap adapted to engage the inclined surface on the container below the rim thereof to create a wedging action between the skirt of the cap and the inclined surface on the container, and means in said skirt for engaging the screw threads on said container to retain the closure in position and to force said gasket against the container. 70

2. A sealed package comprising a container having threads thereon and an inclined sealing surface, a screw closure cap having a depending skirt, a gasket mounted in said skirt at the lower edge thereof adapted to be pressed against said container to form a 85 hermetic seal on said inclined surface when said cap is screwed on said container.

3. A sealed package comprising a container having threads thereon and an inclined surface, a screw closure cap having a 90 depending skirt a gasket mounted in said skirt at the lower edge thereof, said skirt being turned inwardly at its lower edge to support said gasket in position to be pressed against said container to form a hermetic 95 side seal when said cap is screwed on said container.

4. A sealed package comprising a container having threads thereon, a screw closure cap having a depending skirt, a gasket mounted in said skirt, and an inclined annular sealing zone on said container adjacent said gasket, whereby when the closure is screwed on the container a lateral pressure will be exerted against the gasket and the 105 skirt of the cap by said sealing zone. 100

5. A sealed package comprising a container having threads thereon, a closure cap having a cover portion and a depending skirt, an annular bead in said skirt, a gasket in said bead, an annular inclined sealing zone on said container adjacent said bead, and thread engaging means on said skirt for engaging the threads on the container to press said gasket into engagement with said 110 inclined sealing zone to form a side seal therewith when the closure is screwed on the container. 115

6. A sealed package comprising a container having a threaded upper end, a closure cap having a cover portion and a depending skirt, an annular bead at the lower edge of said skirt, a gasket in said bead, and threads in the skirt of said closure above said bead adapted to engage co-operating 120 threads on said container to squeeze said gasket against the side wall of the container to form a hermetic seal. 125

7. A sealed package comprising a container having a threaded upper end, a clo- 130

sure cap having a cover portion and a depending skirt, an annular bead at the lower edge of said skirt, a gasket in said bead, an annular inclined sealing zone adjacent said bead, and threads in the skirt of said closure above said bead adapted to engage cooperating threads on said container to squeeze said gasket against the side wall of the container to form a hermetic seal.

10 8. As an article of manufacture, a screw closure cap having a bead in the skirt thereof below the screw threads in said closure adapted to receive a gasket, whereby when said closure is screwed on a container

15 a hermetic side seal is formed.

9. As an article of manufacture, a screw closure cap having a bead at the lower edge of the skirt thereof adapted to receive a gasket and support it by the lower edge of the

20 skirt, whereby when said closure is screwed on a container a hermetic side seal is formed.
